CLAIM

We claim the ornamental design for front portion of a handle and housing assembly, as shown and described.

DESCRIPTION

FIG. 1 is a front perspective view of a front portion of a handle and housing assembly showing our new design;

FIG. 2 is a front view thereof;

FIG. 3 is a left side view thereof, it being understood that a right side view is identical hereto but a mirror image reversal hereof;

FIG. 4 is a top view thereof;

FIG. 5 is a bottom view thereof;

FIG. 6 is a front perspective view of a second embodiment of a front portion of a handle and housing assembly showing our new design, the only difference being the extended handle;

FIG. 7 is a front view thereof;

FIG. 8 is a left side view thereof, it being understood that a right side view is identical hereto but a mirror image reversal hereof;

FIG. 9 is a top view thereof;

FIG. 10 is a bottom view thereof;

FIG. 11 is a perspective view showing front and left side features of a third form of our new design;

FIG. 12 is a front view thereof;

FIG. 13 is a left side view thereof, it being understood that a right side view is identical hereto but a mirror image reversal hereof;

FIG. 14 is a top view thereof;

FIG. 15 is a bottom view thereof;

FIG. 16 is a perspective view showing front and left side features of a fourth form of our new design which includes the features of the third form but with the handle pivoted to an extended position;

FIG. 17 is a front view thereof;

FIG. 18 is a left side view thereof, it being understood that a right side view is identical hereto but a mirror image reversal hereof;

FIG. 19 is a top view thereof; and,

FIG. 20 is a bottom view thereof.

The broken line disclosure of other elements of a handle and housing assembly is provided for illustrative purposes only and forms no part of the claimed design.
